Specification for Design.

Patented Sept. 20, 1921.

Application filed December 14, 1920. Serial No. 430,767. Term of patent 7 years.

To all whom it may concern:

Be it known that I, ARVID G. DANIELSON, a subject of the King of Sweden, residing at Willmar, in the county of Kandiyohi and State of Minnesota, have invented a new, original, and ornamental Design for a Frame for a Paper-Cutter or Similar Article, of which the following is a specification, reference being had to the accompanying drawing, forming part thereof.

The figure is a perspective view of a paper cutter and twine holder showing my new design.

I claim:

The ornamental design for a frame for a paper cutter or similar article, as shown.

ARVID G. DANIELSON. [L. S.]
